DESIGN FOR A HANDBAG OR SIMILAR ARTICLE

Eli Rosenberg, New York, N. Y.

Application May 3, 1939, Serial No. 84,756

Term of patent 3½ years

To all whom it may concern:

Be it known that I, Eli Rosenberg, a citizen of the United States of America, residing in the city of New York, county of New York, and State of New York, have invented a new, original, and ornamental Design for a Handbag or Similar Article, of which the following is a specification, reference being had to the accompanying drawing, forming part thereof.

Fig. 1 is a front view of a handbag or similar article showing my new design.

Fig. 2 is a top plan view thereof.

Fig. 3 is a bottom plan view in open position.

Fig. 4 is a perspective view in open position.

I claim:

The ornamental design for a handbag or similar article, substantially as shown.

ELI ROSENBERG.
